UNITED STATES PATENT OFFICE.

IRA ANTHEY KARNS, OF TULSA, OKLAHOMA.

SAND-SETTLER.

1,397,836.

Specification of Letters Patent.

Patented Nov. 22, 1921.

Application filed April 7, 1921. Serial No. 459,498.

To all whom it may concern:

Be it known that I, IRA ANTHEY KARNS, a citizen of the United States, and a resident of Tulsa, in the county of Tulsa and 5 State of Oklahoma, have invented certain new and useful Improvements in Sand-Settlers, of which the following is a specification.

This invention relates to a sand settler 10 or trap for deep well pumps.

The object of the present invention is to provide a settler which may be easily attached to the working barrel of a deep well pump, and adapted to cause any sand which 15 may be carried into the settler with the oil, water or other liquid being pumped from the well, to be entirely settled or precipitated from the oil or water before the same passes into the working barrel of the pump.

20 Other objects and objects relating to details of construction, combination and arrangement of parts will be hereinafter pointed out in the detailed description to follow.

25 The invention is illustrated by way of example in the accompanying drawings, in which:

Figure 1 is a central longitudinal section of the upper end portion of the settler, 30 Fig. 2 is a similar view of the lower end portion of the settler,

Fig. 3 is a cross section taken substantially on the line 3—3 of Fig. 1,

Fig. 4 is a cross section taken substantially 35 on the line 4—4 of Fig. 2.

Referring to the drawings more particularly 40 10 indicates the head of the settler which consists of a short tubular section with relatively thick walls and a relatively small bore 11, as shown. The upper end of the head is reduced and threaded as at 12, and at an intermediate point of the bore 11 there is formed a wall 13 which is provided with a central threaded opening adapted to receive the threaded end of a tube 14. Below 45 the wall 13 the bore is enlarged as at 15 and said enlargement is provided with threads as at 16 adapted to receive the threaded end of the pipe 17. The enlargement 15 terminates 50 in a second enlargement 18 which is likewise threaded as shown, and adapted to receive the threaded end of the pipe 19. Also the lower end of the head 10 is reduced and threaded as at 20 and adapted to receive the 55 interiorly threaded end of the pipe or casing 21.

The tubular member 14 terminates at its lower end above the lower end of the pipe 17. The lower end of the tubular member 14 is closed by the means of a plug as indicated at 22 and above this plug a portion of the member is perforated as indicated at 23. The lower end of the pipe 17 is connected to a similar pipe section 24 by the means of a sleeve 25. Also the lower end of the pipe 60 section 24 may be interiorly threaded for connecting to other pipe sections, not shown. The lower end of the pipe 19 terminates at a point considerably above the lower end of the outside casing 21, as shown in Fig. 2. 65 The pipe 19 is opened at its lower end as likewise shown, and from this point communicates with the interior of the casing 21; and also communicates with the pipe 17 through the perforated portion 26 of said 70 pipe, said perforated portion being at the upper end of the pipe, as shown in Fig. 1. The lower end of the casing 21 is likewise threaded as at 27 and adapted to receive the one end of a nipple 28, the nipple being 75 preferably reduced as at 29 and threaded at its lower end as at 30, to which a section of pipe may be connected if desired. The casing 21 also has an upper end portion which is perforated as at 31, Fig. 1.

80 In the operation of the present device, the head 10 is suitably connected to the working barrel of the pump by means of a sleeve into which the threaded end 12 may be screwed. The casing 21 will then 85 of course be immersed in oil or water depending upon what is being drawn from the well. The oil or water will pass through the perforations in the portions 31 of the casing 21 and from thence pass downwardly 90 as indicated by the arrows until the lower end of the pipe 19 is reached, at which time the oil or water must then pass upwardly and into the pipe 19. At this period any sand carried by the oil or water will to a 95 great degree be precipitated or settled, and collected between the casing 21 and the pipe 17, as shown in Fig. 2. The oil or water then continuing will pass from the pipe 19 through the perforations in the 100 upper end portion of the pipe 17 and from thence downwardly through said pipe 17 until it reaches the perforated portion 23 of the tubular member 14, at which time it 105 will pass into the tubular member 14 and from thence be carried through the head member 10 and into the working barrel of 110

the pump. At the time of its passage from the pipe 17 into the tubular member 14 any sand or other foreign matter carried by the oil or water will again have a chance to 5 settle out and separate therefrom and drop in between the tubular member and fall into the lower end of the pipe 17, as shown in Fig. 2.

If desired, an extension may be made to 10 both the casing 21 and the pipe 17 in order to provide a larger receptacle for the settling sand. It may be here pointed out that during the passage of the oil or water through the settler it is subjected to two 15 intervals for separating therefrom, the sand or other foreign matter which the same may carry, one interval being at the time when the liquid passes from the casing 21 upwardly and into the pipe 19, and the 20 other interval being at the time when said oil or water passes from the interior of the pipe 17 through the perforations in the lower end of the tubular member 14. It 25 also may be here pointed out that the tubular members are in graduated spaced relation with one another, the two outermost casings being the greatest distance apart and the two innermost the least distance apart, as shown in the drawing. This arrangement has decided advantage in causing 30 a more thorough separation of the sand from the oil and water.

While I have shown and described the preferred form of my invention, I wish it 35 to be understood that I am aware of the fact that minor changes might be made in the construction, combination and arrangement of parts without departing from the spirit of the invention, as indicated by the 40 appended claims.

I claim:

1. A sand settler of the class described, comprising in combination, a tubular head adapted to be connected at its one end to 45 the working barrel of a pump, a plurality of telescoping tubes extending from the other end of said head, said tubes being

in graduated spaced relation, the greatest space occurring between the outermost tubes, and the innermost tube communicating 50 with the interior of the tubular hood member while the outermost tube has a portion thereof perforated and all the tubes communicating with each other and with the innermost tube at alternate ends. 55

2. A connecting head for a sand settler of the character described, comprising a cylindrical member having a central longitudinal bore and a reduced upper end portion which is threaded and adapted to be 60 connected to the working barrel of a pump, a partition wall in said bore having a threaded central passage, adapted for receiving the exteriorly threaded end of the innermost tube of the sand settler, and said 65 bore having a threaded lower end portion adapted for receiving the threaded end of an intermediate tube of the sand settler, and a reduced threaded portion formed upon the exterior and lower end of said connecting 70 head adapted for receiving the interiorly threaded end of the outermost casing 75 of the sand settler.

3. A connecting head for a sand settler of the character described, comprising a cylindrical member having a central longitudinal bore and a reduced upper end portion which is threaded and adapted to be 80 connected to the working barrel of a pump, a partition wall in said bore having a threaded central passage adapted for receiving the exteriorly threaded end of the innermost tube of the sand settler, said bore having a threaded portion adjacent its lower end, and also an enlarged portion 85 likewise threaded which are adapted for receiving the exteriorly threaded ends of intermediate tubes of the sand settler, a reduced threaded portion formed upon the exterior and lower end of the connecting 90 head, adapted for receiving an internally threaded end of the outermost casing of the sand settler.

IRA ANTHEY KARNS.
